(57) **CLAIM**

The ornamental design for a solar cell module, as shown and described.

DESCRIPTION

FIG. 1 is a front elevational view of a solar cell module showing our new design.

FIG. 2 is a rear elevational view thereof;

FIG. 3 is a right side elevational view thereof, a left side elevational view thereof being a mirror image; and,

FIG. 4 is a top plan view thereof, a bottom plan view thereof being a mirror image.
